(57) **CLAIM**

The ornamental design for a control panel, substantially as shown and described.

DESCRIPTION

FIG. 1 is a top, right-side perspective view of a control panel in a retracted state;

FIG. 2 is a bottom, left-side perspective view thereof;

FIG. 3 is top view thereof;

FIG. 4 is a bottom view thereof;

FIG. 5 is a left-side view thereof;

FIG. 6 is a right-side view thereof;

FIG. 7 is a front view thereof;

FIG. 8 is a top, right-side perspective view of the control panel in an extended state;

FIG. 9 is a bottom, left-side perspective view of the control panel in the extended state;

FIG. 10 is a top, right-side perspective view of the control panel in an extended and tilted state;

FIG. 11 is a bottom, left-side perspective view of the control panel in the extended and tilted state;

FIG. 12 is a right-side view of the control panel in the extended state;

FIG. 13 is a right-side view of the control panel in the extended and tilted state;

FIG. 14 is a top, right-hand perspective view of the control panel in a state of use;

FIG. 15 is a top, right-hand perspective view of the control panel in a state of use; and,

FIG. 16 is a top, right-hand perspective view of the control panel in a state of use.

(Continued)

The broken lines shown in the drawings represent portions of the control panel that form no part of the claimed design.
